US00D650519S

(12) **United States Design Patent**
Maxik et al.

(10) **Patent No.:** US D650,519 S
(45) **Date of Patent:** ** Dec. 13, 2011

(54) **POLE FOR A STREET LIGHT LUMINAIRE**

(75) Inventors: **Fredric S. Maxik**, Indialantic, FL (US); **David Henderson**, Indialantic, FL (US); **Eric Bretschneider**, Clarkston, MI (US); **Addy S. Widjaja**, Palm Bay, FL (US); **Kenneth Marion Bowen**, Indian Harbor Beach, FL (US); **Jean Sundin**, New York, NY (US); **Enrique Peiniger**, New York, NY (US)

(73) Assignees: **Lighting Science Group Corporation**, Satellite Beach, FL (US); **Office for Visual Interaction, Inc.**, New York, NY (US)

(**) Term: **14 Years**

(21) Appl. No.: **29/356,102**

(22) Filed: **Feb. 19, 2010**

(51) **LOC (9) Cl.** 26-99

(52) **U.S. Cl.** **D26/142**

(58) **Field of Classification Search** D26/2, D26/88, 93, 103, 106, 69, 67, 66, 64, 63, D26/65, 71, 75, 76, 80, 120, 121, 124, 128, D26/118, 138, 142, 122, 113, 154, 156, 90, D26/85, 86, 84, 81, 87; 362/183, 294, 295, 362/249.01-249.11; D13/102, 103, 179, D13/180; D25/127, 129, 38; 361/704; 220/570, 220/695, 756; D9/430, 416, 424, 737; D32/53.1, D32/53, 54; 244/118.5, 118.6; 297/245; D6/356, 491, 492, 519, 580; D23/271, 286, D23/234; D12/345; D8/349, 354, 373

(57) **CLAIM**

WE claim, the ornamental design for a pole for a street light luminaire, as shown and described.

DESCRIPTION

FIG. 1 is a side elevation view of the pole for a street light luminaire, with the opposite side being a mirror image thereof;

FIG. 2 is a top plan view of the invention;

FIG. 3 is a bottom plan view of the invention;

FIG. 4 is a front elevation view of the invention;

FIG. 5 is a rear elevation view of the invention;

FIG. 6 is a perspective view of the invention; and,

FIG. 7 is a reduced side elevation view of the invention.

The broken lines shown in FIGS. 1-7 illustrate environmental structure and form no part of the claimed design.

1 Claim, 7 Drawing Sheets
